APPLICATORS

Freddy Homburger, 759 High St., Dedham, Mass.
Filed Oct. 24, 1962, Ser. No. 232,735
16 Claims. (Cl. 15—509)

This invention relates to an article of manufacture and, in particular, to applicators in the form of finger cots carrying a useful material such as a dentifrice, a cosmetic, a medicant, a polishing compound, an abrasive, or, in fact, any material which may conveniently be employed in a small quantity by dabbing and/or rubbing.

The principal objects of the invention are to provide for dispensing a strip of articles of the foregoing kind in quantity, in such form as to be detachable from a roll of separable articles or from a folded length of separable articles; to provide a strip of separable articles of such kind that, when rolled or folded, the useful material does not have contact with itself nor with the dispensing or packaging equipment; to provide a strip of such articles which may be separated into single or multiple units of a size to be easy to carry about in the pocket or pocket-book without danger of soiling the content thereof or the person; to provide a strip of such articles wherein the useful material may be readily exposed for use; and to provide a strip of such articles wherein a single length may include two applicators.

As herein illustrated, the article of manufacture comprises a multi-ply strip having plies which are separable to expose their opposed surfaces, a plurality of spaced bodies of a useful composition attached to the opposed surface of one of the plies, and adhesive detachably connecting the opposed surface of the other ply to the opposed surface of the one ply between the spaced bodies. The adhesive may be situated on the opposed surface of the one ply between the bodies or upon the opposed surface of the other ply, or upon the opposed surfaces of both plies. One ply may comprise a protective strip. Alternatively, both plies may have spaced bodies attached thereto with adhesive intermediate the bodies, arranged with a body on one ply opposite a space on the other ply. The strip is weakened at regular intervals transversely thereof to permit separation of portions of predetermined length, for example, by perforations, enabling the strip to be torn transversely. The places of separation are selected so that each portion has on it a plurality of bodies. The bodies may be disposed transversely or longitudinally, and one or both plies are tubular so that when a length is separated from the strip the finger may be thrust into the tube to enable holding the applicator for use.

The invention will now be described in greater detail with reference to the accompanying drawings wherein:

FIG. 1 is a plan view of a strip of the articles of manufacture, showing the lines of weakness transversely thereof for separation of one unit from the next; each constituting a finger cot having a plurality of bodies transversely thereof;

FIG. 2 is an enlarged longitudinal section taken on the line 2—2 of FIG. 1;

FIG. 2a is a plan view of a portion of the strip with the protector ply removed;

FIG. 3 is a transverse section taken on the line 3—3 of FIG. 1;

FIG. 4 is a transverse section taken on the line 4—4 of FIG. 1;

FIG. 5 is a longitudinal section of a strip of an alternative form;

FIG. 6 is a plan view of a single finger cot after removal from the strip;

FIG. 7 is a section taken on the line 7—7 of FIG. 6;

2

FIG. 8 is an elevation showing the cot applied to a finger for use;

FIG. 9 is a modified form showing the bodies lengthwise thereof;

5 FIG. 10 is an elevation of a strip of articles in the form of a roll;

FIG. 11 is an elevation of a strip of articles in the form of a folded package; and

10 FIG. 12 is a transverse section through a cot designed to be applied to two or more fingers.

Referring to the drawings, the invention comprises an elongate strip 10 of suitable length and width comprised of plies 12 and 14, disposed adjacent each other so as to have coextensive surfaces 16 and 18. At uniformly spaced intervals lengthwise of the ply 12, a plurality of bodies 20 are applied to the opposed surface 16 in spaced parallel relation. In the preferred form, the transverse length of these bodies 20 increase from one end toward the other of the section to which they are applied for 20 reasons which will appear hereinafter. Each body 20 is comprised of a material which is to be used or applied by dabbing, rubbing, or the like, and may be in the form of a paste, cake or discrete particles adhered to the ply by a suitable bonding agent or by its own inherent tackiness. Cosmetics, dentifrices, medicaments, cleaning compositions and abrasives are some of the materials that may be used. The bodies may be strips of a fabricated material having abrasive or polishing characteristics or impregnated with any of the compounds related above 30 attached to the ply 20. The opposed surface 16 of the ply 12 between the bodies 20 is coated with an adhesive 22. The ply 14, in the simplest form of the invention, is fastened to the ply 12 so as to form a protective covering by pressing the portions intermediate the bodies 20 35 into engagement with the adhesive areas 22. The opposed surface 18 of the ply 14 may have adhesive applied to those portions opposite the adhesive on the ply 12 or to the entire surface so that the ply adheres not only to the adhesive-coated portions 22 but also to the body portions 20. The adhesive may be omitted from the ply 12 and the ply 14 adhered thereto by pressing its coated surface against the uncoated areas between the bodies or to the bodies themselves.

45 An adhesive is used which adheres lightly to a material pressed against it or to itself so as to permit separating the plies 12 and 14 easily without tearing of the plies or detaching the bodies 20, or any portions thereof.

As will be seen by reference to FIG. 1, the strip 10 is 50 divided at regular intervals lengthwise thereof by transversely extending lines of weakness 24, which may be in the form of perforations which permit separation by tearing of one section from the next. The spacing of the lines of weakness is chosen so that each section has on it a plurality of bodies 20. Each section is further provided 55 with a weakened line 26 extending longitudinally thereof from one lateral edge, at one end, along a curve to the opposite lateral edge at the opposite edge, so as to provide a finger-shaped article constituting a finger cot. The transverse length of the bodies 20 in each section increasing 60 from a minimum at one end (the tip) to a maximum at the other end (the base) within the line of separation 26.

As will be seen by reference to FIG. 7, the ply 12, to 65 which the bodies 20 are secured, is a flattened tube, hence when a length containing a finger cot is separated from the strip 10, its walls may be separated to permit the finger to be thrust into the tube as shown in FIG. 8. The portion of the tube along the line of separation 26 is heat-sealed so that when the waste piece 28 is removed, the curved side of the cot will form one side of the tube. If desired, the longitudinal edges of the plies may be ad-

hered to each other by means of adhesive or heat sealing to enable use of a material which should be kept moist.

The bodies 20 are shown disposed transversely of the finger cot in FIGS. 1 and 6; however, as shown in FIG. 9, they may be disposed longitudinally thereof, which adhesive interposed between them.

The strip may be made up to provide two cots facing each other, each of which acts as a protective strip for the other in contrast to the strip shown in FIGS. 1 to 6 inclusive, where the ply 14 is solely a protective strip. Thus, as shown in FIG. 5, the ply 12a has bodies 20a spaced therealong with adhesive 22a situated therebetween and the ply 14a has correspondingly positioned bodies 20a and 22a. The plies, however, are assembled so that the bodies 20a on one ply have contact with the adhesive 22a between the bodies on the other ply. Thus, the adhesive on one ply adheres to a body on the other ply and vice versa. This double strip is divided into equal lengths as shown in FIG. 1 to provide individual units, each unit being comprised of two cots which are made available for use by pulling one ply away from the other. Each ply 12a and 14a is tubular so that when a length is detached it can be slipped onto the finger for use. As previously explained, the adhesive used for adhering the two plies is of such a character as easily to release the material to which it is adhered so as not to damage the material or break part of its away.

Strip material of this character may be supplied in a roll as shown in FIG. 10, for insertion into a coin-operated vending machine, so that, by inserting the proper number of coins, one or more lengths may be discharged and torn off for use. Alternatively, the material may be folded up in zig-zag fashion such as shown in FIG. 11, for packaging in a container, so that one length at a time may be removed for use. It is within the scope of the invention to make the strip wide enough, as illustrated to FIG. 12, so that the tubular portion of the cot will accommodate two or more fingers.

It is evident from the foregoing description that manufacture involves very simple operations such as can be carried out by continuous feed of strip material relative to one or more stations as may be convenient for the application of the bodies, the adhesive, the adhering of the plies to each other, and the perforating of the composite strip to enable separation into individual lengths.

It should be understood that the present disclosure is for the purpose of illustration only and that this invention includes all modifications and equivalents which fall within the scope of the appended claims.

I claim:

1. An article of manufacture comprising coextensive plies of flexible material situated face-to-face, a plurality of spaced bodies of useful composition attached to the face of one of the plies, said spaced bodies and the portion of the ply to which they are attached collectively constituting an applicator for the compound, and adhesive detachably connecting the plies face-to-face.

2. An article of manufacture according to claim 1, wherein there is adhesive on the face of one ply between the bodies connecting the plies face-to-face.

3. An article of manufacture according to claim 1, wherein there is adhesive on the face of one ply between the bodies of that ply connecting the plies face-to-face.

4. An article of manufacture according to claim 1, wherein there is adhesive on the face of one ply situated between the bodies on the face of the other ply attaching the plies face-to-face.

5. An article of manufacture according to claim 1, wherein there is adhesive on the face of each play situ-

ated between the bodies on the face of the one ply attaching the plies face-to-face.

6. An article of manufacture comprising coextensive flexible plies of indefinite length situated face-to-face, a plurality of spaced groups of bodies distributed lengthwise of the plies, each group being comprised of spaced bodies of useful composition attached to the face on one ply, each group of spaced bodies and the portion of the ply to which it is attached collectively constituting an applicator for the compound, and adhesive detachably connecting the plies face-to-face.

7. An article of manufacture comprising a multi-ply strip, the plies of which are separable to expose the opposed surfaces, a plurality of spaced bodies of non-adhesive composition on the opposed surfaces of each ply, adhesive on the opposed surfaces between said spaced bodies, said bodies on the opposed surfaces being displaced so that a body on one ply lies opposite a space between adjacent bodies on the other ply, said adhesive on the respective plies having contact with the bodies on the opposed plies.

8. An article of manufacture according to claim 1, wherein the bodies of composition and adhesive are disposed transversely of the length of the strip.

9. An article of manufacture according to claim 8, wherein the bodies of composition and adhesive are disposed transversely of the length of the strip within uniformly spaced portions of equal length divided by lines of weakness which enable separating successive lengths from the strip, each length having intermediate its ends said bodies of composition.

10. An article of manufacture according to claim 1, wherein the bodies of composition and adhesive are disposed longitudinally of the strip.

11. An article of manufacture according to claim 1, wherein the strip is divided by longitudinal spaced lines of weakness which enable separating the strip transversely at said lines into portions of equal length.

12. An article of manufacture according to claim 1, wherein the strip is perforated at equally spaced intervals to enable tearing successive portions from the strip, each of which has on it a plurality of bodies, and the plies of each portion are separable to expose the opposed surfaces.

13. An article of manufacture according to claim 1, wherein the ply having the spaced bodies on it is longitudinally tubular so that each portion constituting an applicator, when separated from the composite strip, has an open end into which the finger may be thrust to hold the portion.

14. An article of manufacture according to claim 1, wherein the longitudinal edges of the plies are sealed.

15. An article of manufacture according to claim 1, wherein each length has a portion removable along one edge to taper the length from base to tip.

16. An article of manufacture according to claim 1, wherein the one of the plies having the bodies on it is longitudinally tubular so that each cot, when separated from the strip, has a tubular portion at its back side and said tubular portion is large enough to accommodate two or more fingers to enable holding the cot for use.
